UNITED STATES PATENT OFFICE

166,534

TOILET PAPER HOLDER

Martin J. Grady, Bridgman, Mich.

Application November 1, 1951, Serial No. 17,228

Term of patent 14 years

(Cl. D4—3)

To all whom it may concern:

Be it known that I, Martin J. Grady, a citizen of the United States, residing at Bridgman, in the county of Berrien, State of Michigan, have invented a new, original, and ornamental Design for a Toilet Paper Holder, of which the following is a specification, reference being had to the accompanying drawing, forming a part thereof, wherein:

The dominant features of my design reside in the portions shown in solid lines.

I claim:

The ornamental design for a toilet paper holder, substantially as shown and described.

MARTIN J. GRADY.
